CLAIM

The ornamental design for a case for medical devices, as shown and described.

DESCRIPTION

FIG. 1 is a top plan view of a case for medical devices, in a closed configuration, showing the ornamental features thereof;

FIG. 2 is a front elevation view of the case of FIG. 1;

FIG. 3 is a right elevation view of the case of FIG. 1;

FIG. 4 is a perspective view of the case of FIG. 1;

FIG. 5 is a top plan view of the case of FIG. 1 in an open configuration;

FIG. 6 is a front elevation view of the opened case of FIG. 5; and,

FIG. 7 is a right elevation view of the opened case of FIG. 5.
